(57) **CLAIM**

The ornamental design for a marker for a tape measure, as shown and described.

DESCRIPTION

FIG. 1 is a perspective view of a marker for a tape measure.
FIG. 2 is a front view of the marker for a tape measure of FIG. 1.
FIG. 3 is a back view of the marker for a tape measure of FIG. 1.
FIG. 4 is a right side view of the marker for a tape measure of FIG. 1.
FIG. 5 is a left side view of the marker for a tape measure of FIG. 1.

FIG. 6 is a bottom view of the marker for a tape measure of FIG. 1.

FIG. 7 is a perspective view of another embodiment of a marker for a tape measure.

FIG. 8 is a front view of the marker for a tape measure of FIG. 7.

FIG. 9 is a back view of the marker for a tape measure of FIG. 7.

FIG. 10 is a right side view of the marker for a tape measure of FIG. 7.

FIG. 11 is a left side view of the marker for a tape measure of FIG. 7.

FIG. 12 is a bottom view of the marker for a tape measure of FIG. 7.

FIG. 13 is a perspective view of another embodiment of a marker for a tape measure.

FIG. 14 is a front view of the marker for a tape measure of FIG. 13.

FIG. 15 is a back view of the marker for a tape measure of FIG. 13.

FIG. 16 is a right side view of the marker for a tape measure of FIG. 13.

FIG. 17 is a left side view of the marker for a tape measure of FIG. 13.

FIG. 18 is a bottom view of the marker for a tape measure of FIG. 13.

FIG. 19 is a perspective view of another embodiment of a marker for a tape measure.

FIG. 20 is a front view of the marker for a tape measure of FIG. 19.

FIG. 21 is a back view of the marker for a tape measure of FIG. 19.

FIG. 22 is a right side view of the marker for a tape measure of FIG. 19.

FIG. 23 is a left side view of the marker for a tape measure of FIG. 19; and,

FIG. 24 is a bottom view of the marker for a tape measure of FIG. 19.

In the figures, a tape measure is drawn in dashed lines and does not form part of the claimed design.
